UNITED STATES PATENT OFFICE.

JOHN F. WHITE, OF CHICAGO, ILLINOIS, ASSIGNOR TO WHITE PRODUCTS COMPANY,
OF CHICAGO, ILLINOIS, A CORPORATION OF ILLINOIS.

HOOD LATCH.

Application filed September 3, 1921. Serial No. 498,294.

To all whom it may concern:

Be it known that I, JOHN F. WHITE, a citizen of the United States, residing at Chicago, in the county of Cook and State 5 of Illinois, have invented certain new and useful Improvements in Hood Latches, of which the following is a specification.

This invention has to do with latches for motor vehicle hoods and the like, and is 10 directed more specifically to an improved hood latch of that type which is carried by the hood and is adapted to engage under continuous spring tension with a stationary keeper disposed within the confines of the 15 same.

The principal object of the invention resides in the provision of such a latch which is characterized by a single reciprocally movable keeper-engaging portion, the dis- 20 engagement of which may be effected either by a turning of the same in either direction through an arc of 90° against limiting stops, or by a downward and inwardly pivoting movement imparted to the 25 handle of the same.

Another object is the provision in such a latch of means for angularly returning the keeper-engaging portion of the same automatically to an operative position relative 30 to the keeper when the said portion is released following the unfastening operation.

The invention further contemplates the provision of such a hood latch which is characterized by a simple construction, a 35 neat and pleasing appearance, and a high degree of efficiency in operation.

Other objects and advantages of the invention will become apparent as the nature of the latch is more fully understood 40 from the following description and accompanying sheet of drawings, wherein is set forth what is at present considered to be a preferred embodiment of the several features of the invention. This particular 45 structural embodiment, however, is presented primarily for the purpose of exemplifying the invention, and is not intended to restrict unnecessarily the spirit of the same or scope of the claims.

50 In the drawing—

Fig. 1 is a side elevation of the latch of this invention, showing in vertical section the adjacent hood and chassis portion of the vehicle;

55 Fig. 2 is a front elevation of the same;

Fig. 3 is a longitudinal medial section through the latching device; and

Fig. 4 is a transverse section on the line 4—4 of Fig. 3.

Referring now in more detail to the drawings and particularly to Fig. 3 thereof, it will be observed that the latching device of this invention includes a tubular member 10 which is open at its upper end, and is closed—except for a central aperture 11—at its lower end. This aperture serves as a snug guiding bearing for the lower portion of a rod 12 which is adapted to reciprocate longitudinally within said member. The lower end of the member 10 in which the said aperture 11 is formed is preferably solid and is characterized by an upper surface 11^a which forms a flat bottom to the interior of the said member at right angles to the axis thereof and an under surface 11^b which is disposed at a sharp angle to the said upper surface, thereby giving to the lower end of the tubular member 10 an obliquely truncated appearance. The oblique end of the member may be either 75 planular or slightly curved, and is so positioned relative to the keeper as to present its under surface in the general direction thereof for a purpose hereinafter set forth.

The lower extremity of the above mentioned rod 12 is sharply bent into an upwardly inclined hook portion 13 which, while incidentally serving to limit the upward movement of the rod in the tubular member by abutting as shown in Fig. 3 90 against the uppermost portion of the oblique end of the latter, constitutes the keeper engaging means of the device. The upper end of the rod 12 is inserted into a recess in the co-axially disposed stem 14 of a handle 15, and is fixedly positioned therein by means of a short transverse pin 16. The lower end of this stem 14 is provided with a cylindrical enlargement 17 which is adapted to fit snugly within the bore of the tubular member whereby to serve as a centering guide for the upper portion of the rod during the reciprocal movement of the same.

In order to prevent a turning of more than 180° of the rod 12 and handle 15 relative to the tube 10 an annular member 18 is provided which encompasses the upper portion of the said rod at a point immediately below the enlarged portion 17 of the stem 110

of the handle. This member is of the same diameter as the portion 17 and the bore of the tube, and is provided at one side with a rectangular lug 19 which extends radially into a longitudinally disposed guiding recess 20 formed in the bore of the tube 10 and upwardly into a segmental relieved portion 21 formed around the rod 12 in the underside of the bottom of the stem 14. It will be appreciated from this construction that the annular member 18 forms a key which, while adapted to move longitudinally of the bore of the tube with the rod 12 and stem 14, serves to provide a connection between the tube 10 and rod 12 which permits a relative turning therebetween of 180° and no more.

A helical spring 22 encompasses the shank of the rod 12, bearing at its upper extremity against the underside of the aforesaid annular member 18 and at its lower extremity against the annular bottom surface 11^a of the tube 10.

It will be appreciated that the spring 22 in drawing the rod 12 upwardly to a position wherein the hook 13 bears against the oblique under surface 11^b of the end of the tube will, due to the camming action of the hook when drawn inwardly against the oblique surface, cause the rod to turn about its axis and assume a position of rest with the hook against the uppermost portion of the oblique surface at right angles to the hook-engaging portion of the keeper.

The structure hereabove described, which comprises the latch, is pivotally mounted to the side 22 of the hook by means of a short transverse pin 23 which passes through and rotatably supports thereon an apertured ear 24 projecting integrally from one side of the tube 10 intermediate the length thereof. The ends of this pin are journaled in two spaced brackets 25 which extend into the hood through a slot 26 thereof from the sides of an aligned slot 27 in an escutcheon plate 28 which is secured to the outer side of the hood by bolts 29. The pin supporting brackets 25 are positioned adjacent the upper end of the slots 26 in the hood in order that, when the upper end of the latching device pivots outwardly, a projection 30 on the ear 24 will engage with the upper end of the slot 26 on the inner side thereof and serve to limit the said pivoting movement of the latching device in the outward direction from the side of the hood. By pivotally supporting the latching device in this fashion it will be appreciated that the same is adapted to extend obliquely downwards into the interior of the hood through the slot 26 which, incidentally, is of sufficient width to permit free passage of the device therethrough.

A flat apron portion 31 is formed integrally with the tube 10 on the opposite

side thereof from the ear 24 and extends downwardly at an angle with the tube in spaced parallel relation to the side 22 of the hood. This apron portion gradually increases in width as it approaches its lower rounded extremity and functions to provide an efficient covering of attractive design for the lower and otherwise exposed and unoccupied portion of the slot 26 below the tube 10. The keeper 32 employed with the latching device of this invention may be of any suitable construction, but is here shown as an L-shaped member having a tongue 33 pinched inwardly from the upright portion thereof to provide an inverted U-shaped yoke 34 on the underside 35 of which the hook portion 13 of the latch is adapted to engage. The keeper is rigidly carried on the vehicle chassis 36 by means of machine bolts 37 which pass into an adjacent portion of the vehicle chassis through the flanged member 38 adapted to limit the inward movement of the side of the hood.

The operation of the latch will now be described. Assuming, first, that the same is unfastened, it is merely necessary to press the handle 16 downwardly, whereupon the hook 13, which is disposed normally at right angles to the keeper yoke due to the cooperation of the hook with the end of the tubular member 10, will engage with the underside of the keeper yoke. If, on moving downwardly, the hook contacts with the upper side of the keeper yoke due to the fact that the side of the hood is already pressed into its fastened position against the limiting flange 38 or the handle is being held in its outermost pivoting position relative to the side of the hood, the lower end of the latch will automatically be moved inwardly by the camming action of the bevelled underface of the hook 13 on the top of the keeper, and the hook will immediately snap into engagement with the keeper yoke upon reaching a position wherein it has been sufficiently depressed to clear the underside 35 of the same. The unfastening may be accomplished in either of the two hereinafter described ways. One may turn the handle 15 a quarter turn in either direction, which will result without appreciable effort in the release of the hook 13 from the keeper yoke through a downwardly camming and turning movement of the upwardly inclined top surface of the former relative to the edge 35 of the latter. The latch may also be unfastened by accompanying a downward depression of the handle with an inward movement of the same, which will serve to extend the hook 13 downwardly out of engagement with the keeper yoke and also outwardly therefrom whereby, when the pressure on the handle is released the hook 13 will be drawn upwardly by the spring 22 out of engagement with the

keeper. The latch of this invention furthermore provides an excellent handle for raising the hood, and obviates the employment of the customary additional handles for this purpose.

5. I claim:

1. In a device of the character described, the combination with a frame portion and an engine hood movable relative thereto, of 10 an axially reciprocable member pivotally carried by the hood and provided at its lower extremity with a hook portion, stops for limiting the axial rotation of the said member, and a keeper fixedly secured to the 15 said frame portion and adapted to cooperate with the said hook portion.

2. In a device of the character described, the combination with a frame portion and an engine hood movable relative thereto, of 20 an axially reciprocable member pivotally carried by the hood and provided at its lower extremity with a hook portion, means for confining the axial rotation of the said member within an angle of substantially 25 180°, and a keeper fixedly secured to the said frame portion and adapted to cooperate with the said hook portion.

3. In a device of the character described, the combination with a frame portion and 30 an engine hood movable relative thereto, of an axially reciprocable member pivotally carried by the hood and provided at its lower extremity with a single hook portion projecting obliquely upwards at an acute 35 angle to the axis of the said member, means for confining the axial rotation of the said member within an angle of substantially 180°, and a keeper fixedly secured to the 40 said frame portion and adapted to cooperate with the said hook portion.

4. In a device of the character described, the combination with a frame portion and an engine hood movable relative thereto, of 45 a hood latch pivotally attached to the hood and projecting obliquely through an aperture in the same into the interior thereof, said hood latch including an axially reciprocable member pivotally carried by the hood and provided at its lower extremity 50 with a single hook portion, and means for confining the axial rotation of said member within an angle of substantially 180°, and a keeper fixedly secured within the interior 55 of the hood to the said frame portion and adapted to cooperate with the said hook portion.

5. In a device of the character described, the combination with a frame portion and an engine hood movable relative thereto, of 60 a hood latch comprising an obliquely disposed tubular member extending through an aperture of the hood, said member being suspended within the aperture by a pivotal connection with the hood, a latch member 65 mounted within the tubular member for

axial and angular movement, means for confining the angular movement of the latch member within an angle of substantially 180°, said latch member having a handle at its upper extremity without the hood and a 70 hook at its lower extremity within the hood, and a keeper fixedly secured to the frame for engagement by the hook.

6. In a device of the character described, the combination with a frame portion and an engine hood movable relative thereto, of 75 a hood latch comprising an obliquely disposed tubular member extending through an aperture of the hood, the member having a 80 pivotal connection at its upper side to the hood above the aperture and provided on its lower side with an apron overlying the aperture, an upwardly spring-pressed latch member mounted within the tubular member for axial and angular movement, said latch 85 member having a handle at its upper extremity without the hood and an obliquely extending hook at its lower extremity within the hood, and a keeper fixedly secured to the frame for engagement by the hook, 90 whereby to enable the disengaging of the latch and keeper by the downward swinging or angular movement of the former.

7. In a device of the character described, the combination with a frame portion and an engine hood movable relative thereto, of 95 a hood latch comprising an obliquely disposed tubular member extending through an aperture of the hood, the member having a 100 pivotal connection at its upper side to the hood above the aperture and provided on its lower side with an apron overlying the aperture, an upwardly spring-pressed latch member mounted within the tubular member for axial and angular movement, said 105 latch member having a handle at its upper extremity without the hood and an obliquely extending hook at its lower extremity within the hood, a keeper fixedly secured to the frame for engagement by the hook, and means to confine the angular movement of the latch within substantially 180°, whereby 110 to enable the disengaging of the latch and keeper by the downward swinging or angular movement of the former.

8. In a device of the character described, the combination with a frame portion and an engine hood movable relative thereto, of 115 an axially reciprocable member carried by the hood and provided at its lower extremity with a hook portion, a keeper fixedly secured to the said frame portion and adapted to cooperate with the said hook portion, and means to cause the hook portion to rotate into a position wherein its free end is directed toward the keeper.

In testimony whereof I have hereunto 120 125 subscribed my name.

JOHN F. WHITE.
